UNITED STATES PATENT OFFICE.

JAMES A. WARREN, OF DENVER, COLORADO.

PUMPING MECHANISM AND SYSTEM.

Application filed December 26, 1923. Serial No. 682,721.

This invention embodies improvements in pumping mechanism and systems.

While the invention primarily has been devised for use in the pumping out of oil wells, and, equivalently speaking, other deep fluid containing wells or shafts, or, for that matter, in association with fluid or liquid bodies or volumes, generally, encompassing the working barrel of the pump, in immersing or submerging relation, and although for the purposes of simplicity of illustration and description the same may be more conveniently disclosed with reference to oil wells or analogous liquid containing shafts, still it would appear that the essential characteristics of the improvements might well be employed in other pumping relations. It is to be distinctly understood and emphasized at the outset, therefore, that the improvements are not necessarily to be restricted to any one particular sphere of analogous or equivalent usefulness.

In attaining the desired ends of maximum efficiency, durability and economy in operations with a simple combination and arrangement of a minimum number of elements, little liable to get disrupted or otherwise out of order and comparatively inexpensive to manufacture, assemble, repair and install one of the primary objects of my invention has been to devise means for causing the pumping pulsations to be semi-automatically effected, as it were, under an auxiliary or operating pressure fluid supply alternately delivered to the opposite pressure faces of a piston which forms a part of a hollow open-ended or tubular plunger liquid displacing element that has valvular means to control the passage therethrough of the liquid to be pumped, as will herein-after more fully appear.

It is believed, however, that the foregoing as well as other objects and advantages of the invention will be so clearly apparent, as incidental to the following disclosure, that no useful purpose would be served by further enlarging upon the same initially, and with these prefacing remarks, therefore, reference will now be immediately had to the accompanying drawings, illustrating certain practical embodiments of the improvements, in which drawings like reference characters designate the same parts in the several views, of which latter

Figure 1 is a longitudinal sectional view 55 through the working barrel and associated elements of one form of the pump; Figure 2 is an analogous view on a smaller scale and additionally showing the attachment of a standard oil well working valve, which 60 may or may not be employed with my improvements as desired; Figure 3 is a broken away elevational view, partly in section, more particularly illustrating the pumping apparatus as a system or assembled whole 65 in association with a well; and Figure 3^a is an elevational view of a pressure tank element, which may be and preferably is employed with but which is shown as disconnected from the assembled apparatus of 70 Figure 3, for automatically controlling or maintaining constant the desired pressure through the operating pressure fluid lines of Figures 1, 2 and 3.

First referring specifically to Figure 1, 75 although the same description will generally apply to the other figures, the numeral 10 designates the pump barrel, preferably formed as an integral unit, and it provides for an inlet chamber 11 for the inflow of the 80 fluid or liquid to be pumped, the inlet conduit or passageway 12 thereto being controlled by a check valve element, which may be conveniently referred to as a suctional inlet, lower or foot valve, being actuated to 85 its open position by a combined suctional and pressure force and to its closed position by a combined gravitation and pressure force. This valve is specifically shown as of standard construction, employing an axially bored base-closure valve seat 13 for the pump barrel, a ball valve 14 therefor, and a spider-like crown or cage 15.

The outer end of the foot valve element is preferably associated with the usual 95 strainer 16, which in the drawings is shown attached to a centrally apertured coupling member 17 that has a cylindrical extension 18, for threaded connection with the strainer, and also a reversely disposed cylindrical 100 extension 19 that may be externally threaded for connection with a tubular element, indicated at 20 as the well tubing, and which preferably is formed with an internal conical seat for complementally receiving and 105 seating a conically beveled end of the pump barrel 10.

It is to be particularly noted, however,

that the pump barrel 10 is transversely partitioned, as at 21, to provide for a distinctively separate chamber 22, at the end of the pump barrel distant from the foot valve, which said chamber 22 is wholly out of communication with the inlet chamber 11, being in fact a working cylinder for a piston 23 that is carried by, and more or less intermediate of, a hollow or tubular-like plunger displacement element, the said working cylinder 22 being in communication only with an operating pressure fluid line for the positive actuation of the piston, with its said hollow plunger, as distinguished from its actuation by the actual fluid or liquid being pumped.

One end 24 of the hollow plunger is in communication with said inlet chamber 11, while the other end 25 thereof is shown as being in valve-controlled communication with the space outside of the head of the pump barrel 10, which space as illustrated by the drawings would be the interior of the well tubing 20. It is understood that the well tubing, as distinguished from the well casing and which tubing may be withdrawn from time to time for any purposes as desired, is lowered within and extends entirely through the well casing proper, and in most instances of very deep wells the tubing projects, or extends, a very great distance beyond the lower end of the casing, where the well bore is through rock, shale or other hard formations, but in any instances where the well casing itself should extend approximately to the bottom of the well, then the space above referred to would, of course, be the interior of the well casing. In this latter event, the conical seating of the pump barrel might be substituted for by threaded connection with the strainer element 16, or the coupling element 17 therefor, without any connection with the well casing. In referring to the aforesaid space, therefore, it may be within either the well tubing, or in some instances within the well casing, or the equivalent of either, when the pump is employed in relations other than a well. At all events, the hollow plunger element is reciprocatingly disposed through axial bearing apertures of the partitioning wall 21 and the head 26 of the pump barrel, the end 25 being provided with a suitable check valve control, indicated by the ball valve 27 and spider-like crown or cage 28 therefor.

The wall of the working cylinder 22 is provided with a port 29 that is in communication with one end of the cylinder, on one side of the piston 23, and with a port 30 that is in communication with the other end of the cylinder, on the opposite side of the piston, the ports 29 and 30 being in respective communication with operating pressure fluid line pipes 31 and 32, which may be threaded into apertures 33—34 through the

head 26 of the pump barrel 10, and with the wall itself of the working cylinder formed, if desired, with an elongated portway 35 extending from the aperture 33 to the port 29.

The construction illustrated at Figure 2 is substantially identical with that previously described with reference to Figure 1, excepting for the end portion 24 of the hollow plunger which may be of slightly different structure and the fact that the inlet chamber 11 is made much longer to provide for the attachment of the additional element 36, which may or may not be employed with the other structure, as desired. This attachment 36 is a standard oil well working valve, as will be fully understood without going into details, but which may be briefly described as embodying the plural cup section 37, having an elongated spider-like crown or cage element 38, housing a ball check valve 39, and terminating in a hollow open-ended nipple 40 for threaded attachment to the end 24 of the tubular plunger. When this valve attachment 36 is employed in combined association with the other features of my improvements, and it may be so employed or not as desired, the end part of the portion 24 of the tubular plunger may preferably be provided with a plurality of apertures 41, to permit of the passage therethrough, into the hollow plunger, of the fluid or liquid being pumped, additionally of its passage thereinto through the hollow nipple 40.

At this point it may not be amiss to note that the assemblies of Figures 1 to 3^a are intended for use with a constant operating pressure fluid which is caused to alternately flow in reverse directions through the conduit lines 31 and 32, from and to the same pressure establishing tank or source, or, in other words, that the pipes 31—32 alternately function as inlet and exhaust lines with reference to the working cylinder 22.

The operating pressure fluid conduit lines 31 and 32 are in communication with a fluid pressure establishing source of any suitable character. For the purposes of illustration, although any equivalent means may be employed, this is shown at Figure 3 as including the coupling pipe connections 42 and 43 respectively opening directly into the opposite ends of a pressure establishing cylinder 44, without the interposition of any controlling valve mechanism and actuating means therefor, whether complex or otherwise, and the said cylinder 44 having a piston 45 therein that is reciprocated by a connecting rod element 46 which is actuated by any suitable power, whereby the operating pressure fluid is caused to alternately flow in reverse directions through the lines 31 and 32.

The pipe connections 42 and 43 in turn may have branch pipes 47 and 48 that are in

communication with a tank 49 (Figure 3^a) forming part of pressure regulating means for equalizing or maintaining constant a predetermined desired pressure through the operating pressure fluid lines. The said branch pipes 47 and 48 are respectively provided with the check valves 50 and 51 that open in the direction of flow from the tank 49, so that they check any back pressure to said tank 49.

The tank 49 is also provided with an air pressure inlet line 52 that is supplied by an air pump, not shown, which is actuated in any suitable manner, for instance by coupling up with the connecting rod element 46, and said tank 49 is further provided with a pop-off valve or gage 53, which may be regulated to automatically relieve excess pressure in the tank over the predetermined desired pressure through the operating pressure fluid lines.

I prefer the use of oil as the operating pressure fluid, although any suitable fluid, whether inelastic or elastic, might be employed for supplying the pressure fluid lines, and with the use of oil as the operating pressure fluid or liquid, then the tank 49 would contain a substantial volume of oil on which a head of compressed air would be maintained by the air pump line 52.

For the purpose of illustrating a general application of the equipment shown in Figures 1 to 3^a, inclusive, an oil well or the like is indicated at Figure 3 by the numeral 54, and the usual well casing or lining tubing therefor is indicated at 55.

Operations.

Considering Figures 1 and 3-3^a, the pump piston 23 is illustrated in neutral position, with the connecting rod 46 at rest, so that both the check valves 27 and 14 are shown as seated.

Assuming now that power is applied to the connecting rod 46 to move the pressure cylinder piston 45 to the right, then the operating pressure fluid at the right side of the pressure piston 45 is forced by way of the pipe 32 into the pump cylinder 22 through the port 30, in a direction to actuate the pump piston 23 on its non-pumping stroke, the exhaust from the opposite side of the piston 23 being provided for by the port 29, portway 35 and the pipe 31, in communication with the left end of the pressure cylinder 44. During this non-pumping stroke the foot valve 14 is obviously held firmly seated, by the combined forces of gravitation and the pressure of the volume of liquid thereover, while the check valve 27 is moved to its open position by the rush of liquid passing from the inlet chamber 11 through the hollow plunger into the tubing 20, or its equivalent, owing to the displacement of liquid in the inlet chamber 11

by the entering plunger end 24. On this stroke there is no displacement of the column of liquid, say oil, within the tubing 20, or in other words there is only admitted therein an additional charge of the oil being pumped.

At the end of the non-pumping stroke, the pressure piston 45 is moved to the left, when a reversal of the flow of the operating pressure fluid, say oil, is caused by way of the then inlet pipe 31, the portway 35 and port 29, entering the pump cylinder 22 at the opposite end to that of its former entry, for operating the pump piston 23, with its hollow plunger, on its pumping stroke, the exhaust then being by way of the port 30 and pipe 32, in communication with the right side of the pressure cylinder 44. During this pumping stroke the plunger controlling check valve 27 is obviously maintained firmly seated, owing to the pressure of liquid opposing its direction of movement, so that a column of oil in advance of the now effectively pumping hollow plunger, which column or volume is measured by the cross-sectional area of the tubular plunger and the length of its stroke, is displaced upwardly within and discharged from the tubing 20. At the same time, the foot valve 14 is maintained in its open position by virtue of both the pressure of oil, seeking entrance to the chamber 11 through the inlet 12, and owing to a suctional force in the same direction caused by the tendency to create a vacuum head on the oil in the chamber 11, or rather perhaps in the hollow plunger as the same is withdrawn from the chamber 11.

Substantially the same alternating operations would result, but with increased output, by the use of the pumping mechanism of Figure 2, excepting it would appear that the hollow plunger controlling valve 27 need not necessarily be employed always because, on the pumping stroke, a substantial volume of oil would be forced from the upper portion of the chamber 11 by the working valve 36, or sucker, through the tubular plunger by way of the hollow nipple 40 and the apertures 41, into the well tubing above the pump barrel, the flow of which would open the valve 27 substantially, if employed, even on the pumping stroke. Hence, there would be an auxiliary displacement of oil upwardly within the well tubing 20, in addition to the normal displacement by the tubular plunger, which auxiliary displacement would be approximately equal to the charge of oil pumped by the working valve or sucker 36 itself, up through the tubular plunger, and which charge or volume would function as an elevating column, or analogously to a fluid piston or plunger, whereby there would be a dual concurrent pumping, as it were, providing for maximum discharges at each pumping stroke.

With the arrangements of both Figures 1 and 2, and more particularly viewing Figures 3 and 3^a, the operating oil pressure through the pipe lines 31 and 32 may be maintained substantially constant or stabilized by the employment of the pressure equalizing tank 49 and the elements thereof. For instance, having set the air relief valve or gage 53 to pop-off when the head of compressed air or pressure on the feed supply of oil in the tank 49 exceeds that of the predetermined desired pressure through the lines 31—32, it will be obvious that any excess pressure in the tank 49, caused by the pumping of the air therein through the line 52, will be automatically relieved. It will likewise be obvious that, should the operating oil pressure through the pipe lines 31—32 fall below the predetermined desired amount, or the maintained pressure in the tank 49, there will be an oil supply feed thereto, for stabilizing the same, by virtue of the branch lines 47—48, with the check valves 50—51 therein, which check valves open only, as before described, in the direction of flow from said equalizing or balancing tank 49.

With either of the constructions of Figures 1 or 2, therefore, when combined with suitable operating pressure establishing means, such as shown at Figure 3 or the equivalent thereof, and also as preferably associated with suitable pressure stabilizing means, such as shown at Figure 3^a or the equivalent thereof, it will be clearly apparent from all of the foregoing, it is believed, that the pulsating pumping operations may be thus automatically continued indefinitely, without any mechanically controlled or actuated valvular additions whatsoever, just 40 as long as the pressure piston 45 is being operated.

Although I have thus completely disclosed the improvements, the objects, advantages and functioning of which it is believed will be clearly apparent from the drawings and foregoing disclosure, it will nevertheless be understood that I do not wish to unnecessarily restrict the invention to all of the details exactly as set forth and illustrated, excepting as they may come within the terms of the ensuing claims, or equivalent elements or combinations thereof, or as fairly interpreted in the light of the specification if requisite.

55 What I do claim, as new and patentable, is:—

1. As an assembled unit of pump mechanism, of the character disclosed, the combination of an elongated hollow plunger carrying a piston between its ends, which ends are respectively provided with inlet means and outlet means, a working valve embodying an elongated hollow base section, the ends of which are respectively provided with 60 inlet means and outlet means, a check valve

controlling the outlet means of said working valve, and means connecting the outlet end of said working valve to and in open communication with the inlet end of said hollow plunger. 70

2. As an assembled unit of pump mechanism, of the character disclosed, the combination of an elongated open-ended tubular plunger carrying a piston between its ends, which ends respectively provide an inlet end and an outlet end, a working valve embodying an elongated hollow base section that has respective inlet means and outlet means at its opposite ends, a check valve controlling the outlet means of said working valve, 80 and means connecting the outlet end of said working valve to and in open communication with the inlet end of said tubular plunger, which said connecting means embodies a cage that houses said check valve and terminates in a communicating hollow open-ended nipple. 85

3. As an assembled unit of pump mechanism, of the character disclosed, the combination of an elongated open-ended tubular plunger carrying a piston between its ends, which ends respectively provide a threaded inlet end and an outlet end, the said inlet end also being radially apertured, a working valve embodying an elongated hollow base section that has respective inlet means and outlet means at its opposite ends, a ball check valve controlling the outlet means of said working valve, and means connecting the outlet end of said working valve to and in open communication with the inlet end of said tubular plunger, which said connecting means embodies a cage that houses said ball check valve and terminates in a communicating tubular threaded nipple attached 105 to said threaded inlet end, of said tubular plunger, in proximity to the radially apertured portion thereof. 100

4. As an assembled unit of pump mechanism, of the character disclosed, the combination of a pump barrel having an end head, a partitioning head and a continuing barrel wall section extending from said partitioning head, the said parts forming a liquid inlet chamber and a piston working cylinder, 110 and portways being provided for an operating pressure fluid line in communication with the opposite ends of said cylinder, an elongated open-ended tubular plunger having outlet and inlet ends, respectively, extending through axial bearing apertures of said end and partitioning heads, and carrying a piston disposed within said cylinder, a check valve in controlling association with one of said inlet or outlet ends, and a check valve and seat therefor closing the outer end of said liquid inlet chamber, each of the 115 said check valves being housed in restrained relation against unlimited movement away from their respective seats. 120

5. As an assembled unit of pump mechanism, of the character disclosed, the combination of a pump barrel having an end head, a partitioning head and a continuing barrel wall section extending from said partitioning head, the said parts forming a liquid inlet chamber and a piston working cylinder, and portways being provided for an operating pressure fluid line in communication with the opposite ends of said cylinder, an elongated open-ended tubular plunger having outlet and inlet ends, respectively, extending through axial bearing apertures of said end and partitioning heads, and carrying a piston disposed within said cylinder, a working valve disposed within said liquid inlet chamber and embodying an elongated hollow base section, the ends of which are respectively provided with inlet and outlet means, a check valve controlling the outlet means of said working valve, and means connecting the outlet end of said working valve to and in communication with the inlet end of said hollow plunger.
- 25 6. In pumping mechanism, the combination of a length of tubing, a pump barrel having an end head, a partitioning head and a continuing barrel wall section extending from said partitioning head, the said parts forming a liquid inlet chamber and a piston working cylinder, the said extending section being detachably seated within the lower portion of said tubing, and the said end head having threaded openings for portways leading to the opposite ends of said cylinder, an elongated open-ended tubular plunger having outlet and inlet ends, respectively, extending through axial apertures of said end and partitioning heads and carrying a piston disposed within said cylinder, a check valve in controlling association with one of said inlet or outlet ends, and a pair of pipe lines connected at their lower ends within the threaded openings of said end head and extending upwardly through said tubing.
- 30 7. In pumping mechanism, the combination of a length of tubing, a coupling member for connection with the lower end thereof, adapted for the suspension of a strainer element, and having an internal upstanding seating recess, a pump barrel having an end head, a partitioning head and a continuing barrel wall section extending from said partitioning head, the said parts forming a liquid inlet chamber and a piston working cylinder, the lower end of said extending section being adapted for facile seating within said seating recess, and the said end head having threaded openings for portways leading to the opposite ends of said cylinder, an elongated open-ended tubular plunger having outlet and inlet ends, respectively, operating through said end and partitioning heads and carrying a piston disposed within said cylinder, a check valve in controlling association with one of said inlet or outlet ends, and a pair of pipe lines connected at their lower ends within the threaded openings of said end head and extending upwardly through said tubing.
- 35 8. In pumping mechanism and systems, the combination of a length of tubing, a pump barrel therein having a piston working cylinder, a liquid inlet chamber and portways leading to opposite ends of said cylinder, an elongated hollow plunger carrying a piston between its ends, which ends are respectively provided with inlet means and outlet means, the said piston being disposed within said cylinder and with the outlet and inlet ends of said plunger operating respectively within said tubing and said inlet chamber, a check valve in controlling association with one of said inlet or outlet ends, and a pair of conduit lines extending upwardly through said tubing and leading from a complementary one of said portways into direct communication with a pressure establishing source for concurrently delivering and exhausting, in alternating cycles, an operating pressure fluid through said conduit lines.
- 40 9. In testimony whereof, I affix my signature,
50 JAMES A. WARREN.
